United States Patent Office

Des. 181,453
Patented Nov. 19, 1957

181,453

BOTTLE

David A. Batchelor, Chicago, Ill., and Robert E. Davis, Toledo, Ohio, assignors to Owens-Illinois Glass Company, Toledo, Ohio, a corporation of Ohio

Application January 4, 1957, Serial No. 44,400

Term of patent 14 years

(Cl. D58—6)

Fig. 1 is a side elevational view of a bottle showing our new design.

Fig. 2 is a view similar to Fig. 1 with the bottle rotated 90° about its axis.

Fig. 3 is a bottom plan view.

Fig. 4 is a fragmentary sectional view taken along the line 4—4 of Fig. 2.

Fig. 5 is a sectional view taken along the line 5—5 of Fig. 1.

We claim:

The ornamental design for a bottle, substantially as shown.
